CLAIM

The ornamental design for a video telephone station, as shown and described.

DESCRIPTION

FIG. 1 is a top, front and right side perspective view of a video telephone station showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and

FIG. 7 is a bottom plan view thereof.

The broken line showing of rectangles, arrows and pushbuttons in FIGS. 1 and 2 is for illustrative purposes only and forms no part of the claimed design.

FIG. 1

FIG. 2

FIG. 3

*FIG. 4**FIG. 5*FIG. 6

FIG. 7
